US00D630921S

(12) **United States Design Patent**
Wallimann-Durrer et al.

(10) **Patent No.:** **US D630,921 S**
(45) **Date of Patent:** **** Jan. 18, 2011**

(54) **HEATING ELEMENT**

(75) Inventors: **Leo Wallimann-Durrer**, Alpnachstad (CH); **Hans Arnold**, Alpnach (CH)

(73) Assignee: **Leister Process Technologies**, Kaguswil (CH)

(**) Term: **14 Years**

(21) Appl. No.: **29/335,549**

(22) Filed: **Apr. 17, 2009**

(30) **Foreign Application Priority Data**

Jan. 26, 2009 (EM) 001074975

(51) **LOC (9) Cl.** **08-05**

(52) **U.S. Cl.** **D8/29.1**

(58) **Field of Classification Search** D8/29.1, D8/29.2, 30, 51; 392/379, 383, 384; 219/221, 219/225, 117, 228, 229, 200, 205, 601, 635, 219/638, 642; 294/49, 54.5

See application file for complete search history.
